The ornamental design for a display screen with graphical user interface, as shown and described.

DESCRIPTION

FIG. 1 is a first image in a sequence for the display screen with the graphical user interface showing the new design; FIG. 2 illustrates a second image thereof; and, FIG. 3 illustrates a third image thereof.

The broken lines illustrate the display screen and portions of the graphical user interface that form no part of the claimed design. The subject matter in this patent includes a process or a period in which an image changes into another image. This process or period forms no part of the claimed design.
